STRUCTURE FOR SUPPORTING PLASTER COATING

Roy Phillips, Dallas, Tex.

Application December 20, 1934, Serial No. 758,481

9 Claims. (Cl. 72—118)

This invention relates to elements employed in building construction and it has particular reference to a lathing tie for holding plaster coating to its points of suspension.

5 The principal object of the invention is to provide means for securing the plaster supporting structure to points of securement, that is to say, to the joists and studs of a structure in such manner that the plaster coating may be slightly 10 displaced relative to its points of securement to prevent cracking usually caused by expansion and contraction due to variations in temperature.

Another object of the invention is to provide 15 means with which said ties are associated in a wall or ceiling construction to modify the infiltration of sound and moisture, together with means to minimize vibration and thereby prolong the life of the plaster coating.

20 The invention generally aims to provide means combined to produce a structure of greater permanence, capable of resisting all weather conditions which are instrumental in causing deterioration of the usual plaster finishes. The 25 peculiar construction and assembly of elements by which this is brought about is such that there will be little or no increase in cost over that of present types of plaster supporting structures.

With the foregoing objects as paramount, the 30 invention has particular reference to its salient features of construction and arrangement of parts which will become manifest as the description proceeds, taken in connection with the accompanying drawing, wherein:—

35 Figure 1 is a fragmentary view of a ceiling joist and wall stud at their meeting points, showing in cross section a fragmentary view of the assembly embodying the invention.

Figure 2 is a perspective view of two wall studs, 40 fragmentarily shown with a fragmentary view of the invention in assembled relationship.

Figure 3 is a view similar to Figure 2 showing, instead of wire lath, a fragmentary section of gypsum lathing or wall board.

45 Figure 4 is a perspective view of one form of wall or plaster tie.

Figure 5 is a perspective view of a modified form of wall or plaster tie.

Figure 6 is a perspective view of a further modified example of the wall tie.

Figure 7 is a perspective view of a further modified form of plaster tie showing the manner in which the supporting rods are intercrossed and held by the tie, and

55 Figure 8 is a further example of the invention

showing the manner of insulating the tie from its point of securement.

Plaster coating or wall finish as usually applied has a tendency to expand in hot weather and contract in cold weather. Moisture is likewise effective in causing expansion of the plaster coating while in extremely arid sections of the country, plaster coating is inclined to contract. These different weather conditions cause the plaster coating to deteriorate and crack. The 10 present invention therefore has been designed to overcome the effect of weather conditions and preserve the plaster coating by so suspending the same as to allow its supporting structure to yield 15 relative to its points of securement.

Continuing with a more detailed description of the drawing, 1 designates an ordinary ceiling joist while 2 designates a wall stud. The customary practice is to affix the metal lath 3 directly against the studs 2 by nailing. The structure of the invention shown in Figures 1 and 2 is to first apply strips of corrugated paper 4 or the equivalent to the supporting structure 1 and 2. This insulates the lath 3 from the supporting structure.

The lath 3 is superimposed upon the corrugated paper strips 4 after which the rods 5 are applied. The rods, corrugated paper 4 and lath 3 are all preferably tied together and held in suspension on the supporting structure by one 20 of the several types of wire ties shown in Figures 4 to 7 inclusive or a further modification of these.

The feature common to all of the modified forms of ties is that they are capable of rotative 35 and longitudinal movement relative to the nail or other means by which they are affixed.

Moreover, all of these ties are so constructed as to provide a loop which is preferably at an angle to the longitudinal axis of the body of the 40 tie in order that the loop may receive two rods at relative right angles at their contiguous or intercrossing points. An example of the foregoing is shown in Figures 1 and 2 in which 6 designates the wire tie, the body of which is 45 affixed to the supporting structure by a nail 7. The tie 6 shown in Figures 1 and 2, while it may be one of the several modified forms illustrated in detail, may be likened to the tie structure shown in Figure 4. In this figure it will be 50 noted that a single piece of wire is bent to provide an elongated space in which to receive the nail 7, one end being looped at a, the width of which loop is at an angle relative to the body of the tie. Being at an angle, one of the rods 5 55

may extend through the loop in one direction while another extends therethrough at right angles to the first rod.

In assembling the invention, the clips or ties 5 6 are first applied to the supporting structure by the nails 7, after which the strips 4 are placed in position and by placing the same against the protruding loop *a*, the paper is punctured to allow the loops to extend therethrough. The lath 3 10 is next applied and the loop *a* of the ties protrude through the interstices of the lath. Next the rods 5 are passed in intercrossed relationship through the loops as shown in Figure 2 and are thus held by the ties in close relationship to the 15 lath 3. The plaster supporting structure is thus assembled preparatory to the application of the plaster coating.

It will be observed that spacing or furring is accomplished by associating elements as explained 20 which will allow the required clinching of the plaster coat about the lath 3 and yet prevent the plaster from coming into intimate contact with the supporting structure 1 and 2.

It is also pointed out that in applying the ties 25 6, spacing of the rods relative to the stud or joist will depend upon the position of the nails 7 in the length of the tie. In other words, when the nail 7 is driven through the tie close to the loop, the rods are held firmly against the joist 30 or stud as the case may be but when the nails are spaced from the loop *a* of the tie at or nearer the opposite end of the tie, the loop *a* may be pulled away from the point of securement which will allow the rods as well as the lath 3 to be 35 moved outwardly from the supporting structure. It will be seen that since the tie 6 is allowed to move relative to the nail 7, and in view of the fact that this is the only medium by which the plaster supporting structure is held to the wall 40 structure the plaster coating as well as its supporting structure may move en masse relative to the wall structure. Accordingly, there is little likelihood that the expansion and contraction of the plaster coat due to weather conditions will 45 cause the coat to crack or buckle.

Substantially the same structure is carried out in the example shown in Figure 3 aside from the fact that instead of metal lath, wall boards 8 are employed. As in the previous case, the corrugated paper strips 9 are secured to the studs 10 50 after having first secured the ties 11 to the studs by means of nails 12. The loops *b* of the ties extend between the edges of the wall boards 8 as shown in Figure 3 and the horizontal rods 13 lie 55 in the space between the boards. The vertical rods 14 intercross and overlie the rods 13 and these rods lie flush against the surface of the wall boards 8. At the points where the vertical rods are disposed over the spaces between the 60 boards 8, a nail 15 or other suitable medium is inserted under the rods to prevent them from lying within the intervening space between the boards. When the assembly as described is completed, a plaster coating is applied over the 65 surface to conceal the rods 13 and 14.

In Figure 5, a tie is shown having all of the features of that illustrated in Figure 4 and described but is constructed from a nail 16, one of 70 which is looped at 17 and the head 18 is flattened. The loop 17 is shaped so that it will be at an angle relative to the axis of the nail in order that the loop will receive rods 19 at intercrossed, right angular relationship. This tie is 75 secured to the wall structure by a staple 20, sub-

stituted for the nail 7 employed for securing a tie previously described.

Figure 6 shows a tie 21 shaped to define a loop 22 to receive intercrossed rods and to provide a longitudinal space through which is passed the 5 securing nail.

In Figure 7 is shown a further modified form of wall tie embracing the features of those already described and is comprised of a single piece of wire 23 bent to provide a loop 24 for receiving 10 the intercrossed rods 25.

Figure 8 illustrates a form of the tie similar to that shown in Figure 6 except that the wire 26 is bent so that one end 27 may be turned away from the body of the tie and sharpened so that 15 it will penetrate the insulation, such as the corrugated paper 4 in Figures 1 and 2 and may be crimped to prevent displacement of the insulating medium. This tie is also provided with a looped portion 28 to receive intercrossed rods. 20

In some cases, it may be preferred to produce the wire tie from insulated wire, that is to say, a wire having a tubular covering of rubber or an equivalent material. However, in lieu of a tie so constructed, a piece of rubber or other insulating material 29, shown in Figure 8, may be disposed so as to underlie the tie and a nail 30 having an insulating washer 31 is driven through the tie and the insulation 29 into the wall structure. Thus it will be seen that a thorough insulation against sound and vibration is provided. It will be seen from the foregoing that the peculiar construction of the wire tie is such that it may be adjusted mechanically at the time of its application and is capable of movement relative 35 to its point of securement to adjust itself to a limited or necessary extent to the natural movements of the plaster coating.

Manifestly, the construction shown is capable of considerable modification and such modification as is considered within the scope and meaning of the appended claims is also considered within the spirit and intent of the invention.

What is claimed is:

1. A construction for walls and ceilings including rods extending horizontally around said walls and vertically thereon to overlie said ceiling, in an unbroken line to form a continuous line of reinforcing, a rod tying means movably secured to the wall structure and having a protruding 50 looped portion disposed at an angle relative to its body, a cushioning medium overlying a portion of said tying means, plaster lathing disposed intermediate said cushioning medium and said rods and exposing the looped portion of said tying 55 means to jointly receive said rods for relative movement.

2. A wall and ceiling construction including rods forming a continuous line of reinforcing throughout said wall and ceiling, means capable 60 of sliding and rotating movement relative to their points of securement for receiving and holding said rods for relative movement, a cushioning means interposed between said rods and their stationary supports for insulating the same 65 against the transfer of sound vibrations from said supports to said rods and plaster receiving means interposed between said rods and said cushioning means.

3. A wall and ceiling construction including 70 intercrossing rods forming unbroken lines of reinforcement throughout said construction, stationary supporting means, means secured at spaced points on said supporting means for slideable and rotative movement relative thereto and 75

- having a protruding portion to jointly receive horizontal and vertical rods at their intercrossing points whereby to enable said rod to move relatively and with respect to their stationary supports, a cushioning means and means for insulating said rods from their stationary supports.
4. A wall and ceiling construction in combination with stationary supports, a plaster receiving structure including rods forming a continuous line of reinforcing throughout said wall and ceiling, looped members for securing said rods to said stationary supports having sliding and rotating connection with said supports whereby to be movable relative thereto, and means for insulating said rods from said supports.
5. A wall and ceiling construction, in combination with stationary wall supports, a plaster retaining structure including intercrossing rods, means secured to and movable relative to said stationary supports for tying said rods together and holding the same for movement relative to said stationary supports, said latter means comprising a wire tie having looped ends, one end of which is movably secured to one of said stationary wall supports, the other end having connection with said rods, plaster receiving lath and flexible corrugated means for spacing said lath and rods from said stationary structure.
6. A wall and ceiling construction in combination with stationary wall supports, a plaster receiving structure including means forming continuous lines of reinforcing throughout said construction and suspended from said wall supports for displacement whereby to yield with respect

thereto upon contraction and expansion of said plaster, the suspending means for said structure comprising wire ties looped at one end to movably embrace a securing means affixed in said supports and shaped at their opposite ends to engage said first means, and means for insulating said plaster receiving structure from said stationary supports.

7. In a wall and ceiling construction as set forth in claim 3, said rod receiving means comprising a wire tie having a loop in one end for movably securing the tie intermediate its ends to the stationary supports of said wall and ceiling and having its opposite end turned at an angle to said loop to receive said rods whereby the latter will be movable relative to said supports.

8. In a construction as set forth in claim 2, said rod receiving and holding means comprising a wire bent to define an elongated space intermediate its ends to adjustably receive a securing means and having a looped portion at one end bent away from the longitudinal axis thereof to jointly receive a pair of rods.

9. In a wall and ceiling construction as described in claim 1, said rod tying means further comprising a member arranged to normally lie flush against the stationary supports of said wall and ceiling having a portion for jointly holding said rods and means arranged to be passed through said member at any point intermediate its ends to secure said member to said supports whereby the said member will be self adjusting upon contraction and expansion of a plaster coat.
